(57) **CLAIM**

The ornamental design for a convenience panel, as shown and described.

DESCRIPTION

FIG. 1 is a perspective view of a convenience panel, incorporating the new design; the convenience panel is shown mounted onto the front of an electrical enclosure, which is shown in broken lines and forms no part of the design to be patented;

FIG. 2 is a perspective view of the convenience panel of FIG. 1;

FIG. 3 is a front view of the convenience panel of FIG. 1;

FIG. 4 is a top view of the convenience panel of FIG. 1;

FIG. 5 is a bottom view of the convenience panel of FIG. 1;

FIG. 6 is a right side view of the convenience panel of FIG. 1; and,

FIG. 7 is a left side view of the convenience panel of FIG. 1.
